Inventor
George H. Tilford.

UNITED STATES PATENT OFFICE.

GEORGE H. TILFORD, OF PROVIDENCE, RHODE ISLAND, ASSIGNOR OF ONE-HALF TO GEORGE A. KEACH, OF PROVIDENCE, RHODE ISLAND.

CHARM, HAT-PIN, &c.

No. 872,697.

Specification of Letters Patent.

Patented Dec. 3, 1907.

Application filed February 26, 1907. Serial No. 359,418.

To all whom it may concern:

Be it known that I, GEORGE H. TILFORD, a citizen of the United States, residing at the city of Providence, in the county of Providence and State of Rhode Island, have invented certain new and useful Improvements in Charms, Hat-Pins, and the Like, of which the following is a specification, reference being had therein to the accompanying drawing.

This invention relates to the construction of a charm, setting, hat-pin head, or the like, and has for its object to provide a device of this character constructed of a plurality of parts or members, which members may be connected together to produce the finished article without the use of solder.

It is well known in the manufacture of inexpensive jewelry that numerous advantages are obtained by being able to assemble the parts without the use of solder. A particular disadvantage in the use of solder is the discoloration of the finished parts upon the application of heat necessary to melt the solder, which is entirely obviated in articles formed of my improved construction.

Another feature of my device is that the parts may be assembled very rapidly and without the employment of skilled labor.

The invention is fully set forth in this specification and more particularly pointed out in the appended claims.

In the accompanying drawings: Figure 1—is a side elevation showing a finished hat-pin head and a portion of the pin stem. Fig. 2—is a detail in perspective of the upper plate of the head. Fig. 3—shows a detail of one of the side members showing the inner face thereof. Fig. 4—is an edge view of said side member looking upward from the lower edge. Fig. 5—is a detail of the fastening plate. Fig. 6—is a detail, partly in section, of the center hub to the upper end of which the fastening plate is secured. Fig. 7—shows the top plate in section and the inner face of one of the side plates, the locking fingers in said side plate engaging said top plate whereby the two members are connected together. Fig. 8—is an edge view of the head showing the side members in section and in position on the central hub, and also showing the ends of the fastening plate as having been passed through apertures in said side plates to hold the latter firmly in position. Fig. 9—is a plan view of the head

with the top plate removed showing the rounded edges of the side plates and the fastening plate engaging said side plates to hold them together.

Referring to the drawings at 1—1 are the two side members of the hat-pin head or charm. These members may be made in any desired design or form and of any desired material but the same are preferably struck up from a soft, pliable sheet metal adapted to have its edges bent around to meet each other at their ends in the manner illustrated in Fig. 9. In the formation of these members pliable fingers or clips 2—2 extend out from the upper edge of each and an aperture 3 is provided through the face of the member for the reception of the fastening plate hereinafter described. The inner face of each member is also provided with a groove 4 preferably semi-circular in form extending from the lower edge of the member up into said aperture 3. At 5, see Fig. 2, is the top or face plate of the article which may be made in any desired form or design but is herein shown as being constructed in a rectangular shape provided at either end with an elongated slot or aperture 6—6 which are for the purpose of receiving the pliable clips or fingers 2—2 extending from members 1. At 7 is a central socket member having an upwardly extending shank 8 across the upper end of which is preferably riveted the fastening plate 9. This plate is preferably made of a thin pliable material adapted to be readily bent to engage the side members. A hole 10 is drilled into the end of said socket member for the purpose of receiving the pin stem 11 when it is desired to use the head for an ornamental hat-pin. Most of these parts are constructed by punch and die work and are shaped by one operation into the desired form ready to be assembled. The edges of the two side members may be left straight or bent around so as to form the ends of the head, if desired, in the manner best illustrated in Fig. 9. After the parts are plated, dipped, or colored the side members 1—1 are placed together on the central socket member 7, the shank 8 of which fits nicely into the grooved portion 4 in the same. The pliable fastening plate 9, which has been previously riveted to the end of this shank, is passed through each of the apertures 3—3 in the side members and the ends of the same bent down on the outside of 105

110

these members in the manner illustrated in Fig. 8, thereby holding said plates securely in position on the socket member. The top plate 5 is then placed onto the upper end of 5 these members the clips or fingers 2—2 passing through the slots 6—6 in said plate and are bent over at either end in the manner illustrated in Fig. 7, securely fastening said plate in position. The pin stem is then 10 forced into the drill hole 10 in the socket member and the hat-pin is completed without the use of solder.

When it is desired to use this head as a charm, or setting, the pin-stem is removed 15 and a ribbon, chain or other suspending device may be readily attached to this socket member.

A charm, setting, hat-pin or the like of my improved construction may be made very 20 rapidly without the employment of skilled labor, thereby reducing the cost of production to a minimum.

Having thus described my invention, what I claim as new and desire to secure by Letters 25 Patent, is:

1. An article of jewelry comprising side members provided with attaching fingers, a top plate engaged by said fingers, and a member located between said side members and 30 having a socket, said member being also provided with flexible means to engage the adjacent portions of said side members.

2. An article of jewelry comprising side members provided with attaching fingers, a top plate engaged by said fingers, a member 35 provided with a socket and located between said side members, and a flexible fastening plate carried by said socket member engaging said side members.

3. An article of jewelry comprising a top plate, side members having means for engaging said top plate, and a member having a socket, and also provided with flexible means for engaging said side members.

4. An article of jewelry comprising a top plate, a plurality of side members, flexible means for uniting said plate and said side members, and a member having a socket and provided with flexible means for engaging said side members.

5. An article of jewelry comprising a top plate, side members having means for engaging said top plate, a member provided with a

socket and interposed between said side members, and a flexible fastening plate carried by the socket member and engaging 55 said side members.

6. An article of jewelry comprising a slotted top plate, side members having fingers engaging the slots of said plate, said side 60 members being provided with openings, and a member provided with a socket to receive a pin and located between said side members and having a flexible fastening plate extended through the openings in said side 65 members.

7. An article of jewelry comprising a slotted top plate, side members having fingers engaging the slots of said plate, said side 70 members being grooved, and a member provided with a socket to receive a pin and fitting in the grooved portions of the side members and provided with flexible fastening means engaging said side members.

8. An article of jewelry comprising a top 75 plate, side members provided with means for engaging said top plate, said side members being grooved and provided each with an opening, and a member having a socket to receive a pin and fitting in the grooved portions 80 of said side members and provided with a locking plate extended through the openings of said side members.

9. An article of jewelry comprising a top plate, side members engaging said top plate, 85 a member interposed between said side plates and having a socket in its exposed end, and a securing plate at the other end of said interposed member engaging said side members.

10. An article of jewelry comprising a top plate, side members secured thereto and each provided with a groove, a pin-supporting member having a shank fitting in the grooves of said side members, the exposed 95 end of said pin-supporting member being provided with an aperture to receive a pin, and a securing plate at the other end of said pin-supporting member engaging said side members.

In testimony whereof I affix my signature in presence of two witnesses.

GEORGE H. TILFORD.
